GUMMING DESK CLIP

Application filed October 2, 1929. Serial No. 396,695.

This invention relates to improvements in portable gumming desks and more particularly to a clip for use in conjunction therewith.

5 One object of this invention is an improved desk clip of few and simple parts which are adapted to be readily assembled to form a simple, efficient and inexpensive device.

10 Another object of this invention is a desk clip which permits the ready removal of individual loose blanks secured thereby without disturbing the remaining blanks, and without injuring the blank so removed.

15 Other objects will appear from the detailed description.

In the drawings comprising but a single sheet of seven figures, numbered Figures 1 to 7 inclusive, one embodiment of the invention is diagrammatically set forth;

20 Fig. 1 is a view of one end of the upper jaw member of the desk clip;

Fig. 2 is a top view of the gumming desk and desk clip assembly with the desk broken away;

25 Fig. 3 is an end view of the upper jaw member shown in Fig. 4 looking from the left of the latter figure;

Fig. 4 is a top view of the upper jaw member;

30 Fig. 5 is a view of the other end of the upper jaw member;

Fig. 6 is a section of the desk and clip taken along the line 6-6 of Fig. 2 looking in the direction of the arrows;

35 Fig. 7 is a perspective of the gumming desk and desk clip in assembled condition.

Like reference characters designate corresponding parts throughout the several figures.

40 Referring to Fig. 7, the gumming desk comprises the desk 28 and the clip 27; the latter in cooperation with a stop member 41 and the headblock 40, which is undercut at 50, tending to retain the loose blanks in normal position. A second clip 29 and an angle-plate 42 may be provided, both being secured to the desk 28, and tending to retain the blanks, detached from the clip 27, together.

45 The angle-plate 42 tends to align the edges of the loose blanks held by the clip 29. A

moistening pad 26 may also be secured to the desk 28.

The surface 21-21 (Fig. 6) of the desk 28 constitutes one jaw or clamping surface of each of the clips 27 and 29. A pair of ears 14 (Figs. 2 and 6) are suitably secured to the desk 28. In the embodiment disclosed in the drawings these ears are secured to the end wall of the desk. The plate 8 constituting

55 the upper jaw of clip 27 is provided with a clamping edge having a curved lip as indicated at 49 in Figs. 1, 5 and 6 of the drawings. Opposite sides of the member 8 may be bent substantially at right angles to the body

thereof, as indicated in Figs. 1, 3 and 5, to 65 constitute the side walls 43 (Fig. 1) and 44 (Fig. 5). The side wall 44 is provided with a circular recess 11, and the side wall 43 with an elongated recess 10. A blotter holder 13 is provided having a plurality of raised punch-

70 ings 18 constituting holders wherein the corners of the blotter may be inserted to retain the blotter in position with respect to the blotter holder 13. The blotter holder is like-

75 wise provided along oppositely disposed sides with a pair of ears 46 (Figs. 6 and 7), similar to the ears or side walls 43 and 44 of

plate 8, constituting angular extensions thereof, each of said ears being provided with a circular recess. The blotter holder 13 and

80 upper jaw member 8 are pivotally secured to the desk 28 by means of the pivoting rod 15 which passes through the recesses 10 and 11 of the upper jaw member 8, through the re-

85 cesses in the ears of the blotter holder 13 and through the apertures in the ears 14.

85 The side walls 46 of the blotter holder 13 are bent inwards at the corners 47 and 48 (Figs. 2 and 6) to constitute flanges or

90 fingers 45 (Fig. 6), which fingers project inwards beneath the plate 8. When the blotter holder 13 is turned about the pivoting rod 15, the fingers 45 engage the under-

95 surfaces of the plate 8, and the jaws of the clip 27 are separated by moving the plate 8, constituting the upper jaw, relative to the surface 21, constituting the lower jaw, of the

100 clip 27, thereby increasing the separation between the surface 21 and the curved lip 49

constituting the clamping edge of the upper jaw.

The jaws of the clip 27 are held normally closed under the tension of a spring, and to that end a pulley wheel 17, slidably journaled upon the rod 16, is positioned beneath the surface 21 of desk 28. A cable 12 passes over the groove of pulley wheel 17, through an elongated slot 19 (Fig. 2) in the desk surface 21, and terminates in a hook 31 (Fig. 6) which engages in one of the apertures 30 of the punched bracket 9 formed on the plate 8. An angle bracket 22 (Fig. 6), which is secured to the under-side of desk 28, is adapted to receive a machine screw or bolt 32. The cable 12 is retained under tension by means of a coiled spring 20 (Fig. 6) forming a continuation of said cable and anchored to the screw bolt 32.

Whenever the outer (left-hand) end of blotter holder 13 is depressed, its inner (right-hand) end moves radially upwards about the rod 15, causing the fingers 45 to engage beneath the upper jaw of plate 8, imparting an upward movement to plate 8 against the increasing tension exerted by the coiled spring 20 upon the cable 12 and consequently upon the plate 8. When pressure is removed from the outer end of blotter holder 13, the plate 8 is restored to its normal position under tension of spring 20, and the curved lip 49 functions to clamp any loose blanks positioned thereunder.

The headblock 40 is beveled or undercut as indicated at 50, thereby tending to retain the blanks secured by the clip 27 in position and in alignment.

The punched bracket 9 extends from a point adjacent an imaginary transverse medial line extending across the plate 8, to a point adjacent the side wall 44. Similarly, the holes punched in the bracket 9 extend from a point adjacent the centre to a point adjacent the side wall 44 of the plate 8. The hook 31 is adapted to engage with any hole 30 in the punched bracket 9, and as the pulley 17 is slidably journaled upon the rod 16, the pulley may be moved upon rod 16 as desired, so as to position the pulley opposite the particular hole 30 in which hook 31 may happen to be engaged. A series of apertures in the angle bracket 22, each aperture adapted to receive the machine screw or bolt 32, may likewise be provided so that the position of the machine screw may be changed relative to the bracket 22, as desired, for the purpose of maintaining the machine screw 32, spring 20, cable 12, pulley 16, hook 31, and aperture 30 wherein said hook may be engaged, in a plane substantially at right angles to bracket 9. When the tension exerted by spring 20 via cable 12 and hook 31 is applied adjacent the imaginary transverse medial line extending across the plate 8, the pressure exerted by the lip 49 upon the blanks positioned there-

under will be substantially uniform at all points throughout the length of the lip 49. When the pressure exerted by spring 20 is applied to the plate 8, off centre, the pressure exerted by the lip 49 upon the blanks positioned thereunder will vary at different points throughout the length of the lip 49, said pressure being the least at the point most remote from the point of application of the spring tension, so that if the hook 31 is inserted in the lowest aperture 30 of the angle bracket 9, the pressure exerted by the lip 49 upon the blank positioned thereunder, will be greatest adjacent the aperture 30 wherein the hook is engaged, and will gradually decrease along the length of the lip 49 as we approach the upper corner adjacent the end wall 43.

The aperture in the side wall 44, through which the rod 15 is journaled, is circular, while the aperture 10 in the wall 43 is elongated, so that if the pressure exerted by the spring 20 upon the plate 8 is applied adjacent the end wall 44, there will be a tendency for the plate 8 to move upwards until the lower portion of the elongated slot 10 engages with the rod 15, thereby effecting a gradually increased separation between the lower jaw 21 and the lip 49 of the plate 8 or upper jaw, this separation being greater as we approach the end wall 43. By virtue of these structural features, any blank held upon the surface 21 under the pressure exerted by lip 49 of the plate 8 or upper jaw, will be comparatively loosely secured at the upper left hand corner, but held more and more securely in position as we approach the lower left hand corner of the blank. It will therefore be possible to detach the top blank from the remaining blanks and from the clip 27 by exerting a withdrawal motion adjacent the right hand edge of the blank. During this operation the upper left hand corner of said blank will be freed from the pressure of the curved lip 49, thereby facilitating the removal of the top blank without tearing or mutilation.

What is claimed is:

1. In a desk clip for holding loose leaf blanks and in combination, a supporting member comprising one jaw of the clip, a second member having depending side walls having apertures therein for pivotally mounting said second member with respect to said first member, one of said apertures being larger than the other to permit said members to apply different pressures to different portions of one margin of said blanks, and means secured to said second member at a point offset from its medial line for exerting said pressure.

2. In a desk clip according to claim 1 characterized in this that said means is a coiled spring, one end of which is connected to the

second member and the other end of which is connected to the supporting member.

3. A desk clip for holding loose leaf blanks comprising a pair of jaw members pivotally connected at two points, the connection at one point being so formed as to permit relative movement of the jaw members in a direction transverse to the pivotal axis, and means tending to force the jaw members into gripping engagement against the loose leaf blanks to be held thereby and co-operating with said pivotal connection to produce greater pressure between the gripping faces of the jaw members at one point than at other points.
4. A desk clip for loose leaf blanks comprising a supporting member constituting one jaw of the clip, a second member constituting the other jaw of the clip and supported by the supporting member at two points to form a pivotal connection therebetween, the connection at one point being such as to permit movement of the second member in a direction transverse to the pivotal axis, and means for applying pressure to the second member at a single point tending to close the jaws with graduated pressure along the gripping faces thereof.

In witness whereof, I hereunto subscribe my name this 30th day of September 1929.
